US00D834187S

(12) **United States Design Patent** (10) **Patent No.:** **US D834,187 S**
(45) **Date of Patent:** **** Nov. 20, 2018**

(54) **DISINFECTING CAP**(71) Applicant: **Becton, Dickinson and Company**,
Franklin Lakes, NJ (US)(72) Inventor: **Kevin M. Ryan**, Whitehouse Station,
NJ (US)(73) Assignee: **Becton, Dickinson and Company**,
Franklin Lakes, NJ (US)(***) Term: **15 Years**(21) Appl. No.: **29/624,402**(22) Filed: **Oct. 31, 2017****Related U.S. Application Data**(63) Continuation of application No. 15/408,278, filed on
Jan. 17, 2017, and a continuation of application No.
15/408,187, filed on Jan. 17, 2017.(51) **LOC (11) Cl.** **24-02**(52) **U.S. Cl.**USPC ..... **D24/130**(58) **Field of Classification Search**USPC D24/127-131, 112-114, 133, 186;

Primary Examiner — David Muller(74) *Attorney, Agent, or Firm* — Dickinson Wright, PLLC(57) **CLAIM**

The ornamental design for a disinfecting cap, as shown and described.

DESCRIPTION

FIG. 1 is a top perspective view of a disinfecting cap embodying my new design;

FIG. 2 is a bottom perspective view thereof;

FIG. 3 is a bottom plan view thereof;

FIG. 4 is a side elevation view thereof;

FIG. 5 is a top plan view thereof; and,

FIG. 6 is a side cross-sectional view thereof, taken along the line 6-6 in FIG. 3.

The dashed broken lines in the drawings represent portions of the disinfecting cap that form no part of the claimed design.

1 Claim, 6 Drawing Sheets(56)
